(74) Attorney, Agent, or Firm — Taylor English Duma LLP

(57) **CLAIM**

The ornamental design for a weld outlet, as shown and described.

DESCRIPTION

FIG. 1 is an isometric view of my new design;

FIG. 2 is a front view and a back view of the design of FIG. 1;

FIG. 3 is a first side view and a second side view of the design of FIG. 1;

FIG. 4 is a first end view of the design of FIG. 1; and,
FIG. 5 is a second end view of the design of FIG. 1.

The broken lines in the drawings depict portions of the weld outlet which form no part of the claimed design.

1 Claim, 5 Drawing Sheets(56)
